(57) **CLAIM**

The ornamental design for a high-profile refrigerated floral merchandiser unit, as shown and described.

DESCRIPTION

FIG. 1 is a perspective view of a refrigerated floral merchandiser unit showing my new design. The shelves are shown in ghost and do not form a part of this design.

FIG. 2 is a top plan view thereof.

FIG. 3 is a front elevational view thereof; and,
FIG. 4 is a left side elevation thereof, the right side elevation being a mirror image.

The rear side and the bottom of the refrigerated floral display unit do not form a part of the design.
